(57) **CLAIM**

I claim the ornamental design for a scalloped food service cover, as shown and described.

DESCRIPTION

FIG. 1 shows a perspective view of the scalloped food service cover.

FIG. 2 is a side elevation view of the scalloped food service cover.

FIG. 3 is a front elevation view of the scalloped food service cover.

FIG. 4 is a plan view looking downwardly onto the scalloped food service cover from the top.

FIG. 5 is a bottom plan view of the scalloped food service cover; and,

FIG. 6 is a top perspective view of an alternative embodiment of the scalloped food service cover.
